RAILWAY TRAFFIC CONTROLLING APPARATUS

Frank T. Pascoe, Scott Township, Allegheny County, Pa., assignor to Westinghouse Air Brake Company, Wilmerding, Pa., a corporation of Pennsylvania

Application November 28, 1952, Serial No. 323,049

9 Claims. (Cl. 246—33)

My invention relates to railway traffic controlling apparatus. More particularly, my invention relates to apparatus for controlling signals for governing movements of switching locomotives onto a switching area, such, for example, as one which embodies storage tracks.

From the standpoint of safety, as well as efficiency of operation, it may be required or desirable to permit only one railway vehicle such, for example, as a switching locomotive, commonly termed a "switcher," to work within a given switching area at any given time. In order to save on the cost of maintenance, as well as on the cost of original installation, it may be considered preferable to provide apparatus, for controlling railway traffic governing means for a switching area, which does not require the use of track circuits or other traffic responsive or detecting means within the switching area. Furthermore, steel ties might be used for one or more tracks in some switching areas, and in such cases track circuits within the switching area would not be satisfactory.

An object of my invention is therefore the provision of apparatus for controlling traffic governing means to authorize only one switcher to work over any given switching area at any given time.

Another object of my invention is the provision of apparatus for controlling traffic governing means for a stretch of track which is not equipped with track circuits or other traffic responsive means.

A feature of my invention for accomplishing these objects is the provision of traffic governing means such, for example, as a signal of any suitable type, adjacent each point of entrance for a stretch of track such, for example, as a switching area for governing the movements of railway vehicles onto the stretch of track.

Another feature of my invention is the provision of suitable traffic responsive means such, for example, as two track circuits, one in advance of, and the other in the rear of, the traffic governing means adjacent each point of entrance for a stretch of track such, for example, as a switching area.

Still another feature of my invention is the provision of means controlled by such traffic responsive means in response to a vehicle approaching in the rear of the traffic governing means for any given point of entrance to a given stretch of track for placing the corresponding traffic governing means in condition to direct the vehicle to enter the stretch of track only if there is no other vehicle on the stretch of track.

Still another feature of my invention is the provision of means controlled by said traffic responsive means, in response to a first vehicle passing the traffic governing means for any given point of entrance to a given stretch of track, for placing the corresponding traffic governing means in condition to stop another vehicle while the given stretch of track is occupied by the first vehicle.

Yet another feature of my invention is the provision of means controlled by the traffic responsive means in response to a vehicle leaving the given stretch of track

2

for preparing the traffic governing means for directing another vehicle to enter the given stretch of track in response to the approach of said another vehicle.

My invention, as indicated by the foregoing paragraphs concerning its objects and features, relates to railway traffic controlling apparatus for controlling traffic governing means such, for example, as signals of any suitable type for governing the movement of vehicles such, for example, as switchers onto a given stretch of track such, for example, as a switching area, which is not equipped with track circuits or other traffic responsive means; and comprises traffic responsive means such, for example, as two track circuits for each exit point, and also two track circuits, one in the rear of, and the other in advance of, the traffic governing means adjacent each point of entrance for the given stretch of track; traffic control means such, for example, as a traffic control relay for each exit point for the given stretch of track, each of which is controlled by the traffic responsive means to become energized only when a vehicle leaves the given stretch of track at the corresponding exit point, and each of which then remains energized until the vehicle and all the cars, if any, which it may be pulling, have passed the traffic responsive means adjacent the corresponding exit point; master control means such, for example, as a master control relay controlled by the traffic responsive means and by the traffic control relays to become energized when the vehicle and any cars which it may be pulling leave the switching area, and to then remain energized until a vehicle approaching the given stretch of track passes the traffic governing means at an entrance point; and means controlled by the traffic responsive means for each entrance point and each exit point, and by the traffic control means and master control means, for controlling the traffic governing means for each entrance point to authorize a vehicle to enter the given stretch of track only if it is not already occupied by another vehicle.

I shall describe one form of apparatus embodying my invention, and shall then point out the novel features thereof in claims.

The accompanying drawing constitutes a diagrammatic view showing one form of apparatus embodying my invention for a switching area which is not equipped with track circuits or other traffic responsive means; said apparatus including two track circuits adjacent each of the entrance and exit points, which are designated by the reference characters *a* and *b*, for the switching area; including a signal, designated by the reference character 1S or 2S, adjacent the adjoining ends of the track circuits for each entrance point *a* or *b*, respectively; including a repeater relay, designated by the reference character 1-1ATPR or 2-2ATPR, for use if the point *a* or *b*, respectively, serves as an exit point, each of these repeater relays controlled by front contacts of the track relays for the corresponding exit point; including a traffic control relay, designated by the reference character 1XSR or 2XSR, for each exit point *a* or *b*, respectively, each controlled by the repeater relay for the corresponding exit point and by the track relay for the first track circuit shunted by a switcher leaving the switching area at the corresponding exit point; including a master control relay, designated by the reference character ENSR, controlled by the traffic control relays and by the first track circuit shunted by a switcher leaving the switching area at any exit point; and including signal relays, designated by the reference characters 1HR and 2HR, each of which is controlled by the track relays and by the traffic control relays and master control relay for controlling signals 1S and 2S, respectively.

Similar reference characters refer to similar parts in the drawing.

A switching area is shown in the drawing, having limit points *a* and *b*, and comprising a main track, designated by the reference character MT, a first storage track, designated by the reference character 1ST, and a second storage track, designated by the reference character 2ST. As shown in the drawing, each of the points *a* and *b* serves at times as an entrance point, and at other times also serves as an exit point. However, point *a*, for example, could be used for only an entrance point, and point *b* could be used as an exit point only, and there could be other points serving only as entrance points and others serving only as exit points, and also other points which could serve as both an entrance and an exit point, as shown for points *a* and *b*.

I shall assume that traffic movements toward the right, as shown in the drawing, are in the eastbound direction, whereas traffic movements toward the left, as shown in the drawing, are in the westbound direction.

In order to simplify the drawing, each track, comprising two parallel series of track rails, is represented by a single line.

Adjacent, and to the west of point *a*, track MT is divided by insulated joints 3 into a first section, designated by the reference character 1AT, and a second section, designated by the reference character 1T. Adjacent, and to the east of point *b*, track MT is divided by insulated joints 3 into a first section, designated by the reference character 2AT, and a second section, designated by the reference character 2T. Each of the track sections is provided with a track circuit including a suitable source of current, such as a battery 4, connected across the rails adjacent one end of the section, and a track relay, designated by the reference character R, preceded by the reference character for the corresponding section, connected across the rails adjacent the opposite end of the section.

A signal, designated by the reference character 1S, is located adjacent the adjoining ends of sections 1AT and 1T for governing switchers entering the switching area in an eastbound direction at point *a*. A second signal, designated by the reference character 2S, is located adjacent the adjoining ends of sections 2AT and 2T for governing switchers entering the switching area in the westbound direction at point *b*. The signals may be of any suitable design such, for example, as the well-known color light type which has yellow and red light units, designated by the reference characters Y and R, respectively, as shown in the drawing.

Each of the relays 1-1ATPR and 2-2ATPR is shown as being of a slow releasing type, to provide a longer closed pickup circuit period for relays 1XSR and 2XSR, respectively. However, it would not be necessary for relays 1-1ATPR and 2-2ATPR to be slow releasing, if relays 1XSR and 2XSR were quick enough to pickup, or if the voltage of the source of current for energizing these relays were high enough.

The control circuits and the signal lighting circuits may be supplied with energy from any suitable source such, for example, as a battery Q, having terminals B and N, as shown in the drawing.

Having described, in general, the arrangement and control of the various parts of one form of apparatus embodying my invention, I shall now describe the circuits and operation in detail.

As shown in the drawing, each of the track sections is unoccupied, and therefore each of the track relays is energized; each of the signal relays 1HR and 2HR is de-energized, and therefore each of the signals 1S and 2S, respectively, is displaying the red or stop indication; relays 1-1ATPR, 2-2ATPR and ENSR are energized; and relays 1XSR and 2XSR are deenergized.

The circuit by which relay 1-1ATPR is energized passes from terminal B, through the front point of contact 5 of relay 1TR, contact 6 of relay 1ATR, and the winding of relay 1-1ATPR to terminal N. Relay 2-

2ATPR is energized by a similar circuit, controlled by relays 2TR and 2ATR.

Relay ENSR is energized by its stick circuit, passing from terminal B, through contacts 13 and 14 of relays 5 1TR and 2TR, respectively, contact 15 of relay ENSR, and the winding of relay ENSR to terminal N.

Lamp R of signal 1S is lighted by an obvious circuit passing from terminal B, through the back point of contact 29 of relay 1HR, and lamp R to terminal N. Lamp R of signal 2S is lighted by a similar circuit, which includes the back point of contact 30 of relay 2HR.

I shall assume that a first switcher approaches signal 1S, preparatory to entering the switching area *a*-*b* at point *a*.

15 When the switcher enters section 1AT, deenergizing relay 1ATR, contact 6 of relay 1ATR opens the circuit traced for relay 1-1ATPR, causing relay 1-1ATPR to be deenergized. Such operation of relay 1-1ATPR at this time, however, performs no useful function.

20 Relay 1ATR, upon becoming deenergized, completes a pickup circuit for relay 1HR, this circuit passing from terminal B, through contacts 13 and 14 of relays 1TR and 2TR, respectively, contacts 18, 19 and 20 of relays 2XSR, ENSR and 1XSR, respectively, contact 21 of relay

25 1ATR, contact 22 of relay 2HR, contact 23 of relay 2ATR, and the winding of relay 1HR to terminal N. Relay 1HR, upon becoming energized, completes its stick circuit, which is the same as its pickup circuit just traced except that it includes contact 24 of relay 1HR instead

30 of contact 23 of relay 2ATR. Relay 1HR, upon thus becoming energized, opens its contact 29 at the back point, thereby extinguishing lamp R of signal 1S, and then closes its contact 29 at the front point, thereby completing a circuit passing from terminal B, through the front point of

35 contact 29 of relay 1HR, and lamp Y of signal 1S to terminal N, for lighting lamp Y of signal 1S.

When the switcher enters section 1T in response to the lighting of lamp Y of signal 1S, relay 1TR will become deenergized, so that its contact 13 will open the pickup

40 and stick circuits, just described, for relay 1HR, causing relay 1HR to again become deenergized. With relay 1HR again deenergized, lamp Y of signal 1S will be extinguished, and lamp R of this signal will again be lighted. When relay 1TR becomes deenergized, its contact 13 also opens the stick circuit traced for relay ENSR, causing relay ENSR to also become deenergized.

When the switcher leaves section 1AT, relay 1ATR becomes energized, thereby opening its contact 21 in the circuit previously described for relay 1HR.

50 When the switcher leaves section 1T and is on the switching area, contact 13 of relay 1TR becomes closed in the pickup and stick circuits traced for relay 1HR, but relay 1HR remains deenergized because contact 19 of relay ENSR and contact 21 of relay 1ATR are open.

55 I shall next assume that a second switcher approaches signal 1S, preparatory to entering the switching area *a*-*b* at point *a*. When the second switcher enters section 1AT, deenergizing relay 1ATR, contact 21 of relay 1ATR becomes closed in the circuits described for relay 1HR, but relay 1HR remains deenergized because contact 19 of relay ENSR is still open. Signal 1S will therefore continue to display the stop indication, and will prevent the second switcher from entering the switching area while it is occupied by the first switcher.

60 I shall now assume that the first switcher leaves the switching area *a*-*b* at point *b*. When the first switcher enters section 2T while leaving area *a*-*b*, contact 9 of relay 2TR becomes opened at its front point, thereby de-energizing relay 2-2ATPR. If relay 2XSR were quick enough acting, or if the voltage of the source Q were sufficiently high, relay 2XSR would close its front contacts during the brief period while contact 11 of relay 2-2ATPR is still closed at its front point after contact 9 of relay 75 2TR becomes closed at its back point, even if relay

2-2ATPR were not of a slow releasing type. However, in order to provide a longer period during which the pickup circuit for relay 2XSR is closed, relay 2-2ATPR, in the particular form of apparatus shown in the accompanying drawing, is of the slow release type.

The pickup circuit by which relay 2XSR becomes energized passes from terminal B, through the back point of contact 9 of relay 2TR, the front point of contact 11 of relay 2-2ATPR, and the winding of relay 2XSR to terminal N. Relay 2XSR, upon becoming energized, completes a first stick circuit which is the same as the pickup circuit just traced except that it includes contact 12 of relay 2XSR instead of the front point of contact 11 of relay 2-2ATPR. Relay 2-2ATPR, upon releasing its contact 11, completes a second stick circuit for relay 2XSR, this circuit passing from terminal B, through the back point of contact 11 of relay 2-2ATPR, contact 12 of relay 2XSR, and the winding of relay 2XSR to terminal N.

When the first switcher enters section 2AT, contact 10 of relay 2ATR will become opened in the circuit for relay 2-2ATPR, which is however already deenergized on account of contact 9 of relay 2TR being open at the front point. Relay 2ATR, upon becoming deenergized, closes its contact 25 in the circuits for relay 2HR, which are, however, already open at contact 19 of relay ENSR and contact 18 of relay 2XSR.

When the first switcher leaves section 2T, so that relay 2TR is again energized, relay ENSR becomes energized by a pickup circuit passing from terminal B, through contacts 13 and 14 of relays 1TR and 2TR, respectively, contact 16 of relay 2XSR, and the winding of relay ENSR to terminal N. Relay ENSR, upon thus becoming energized, again completes its stick circuit previously traced.

While relay 2ATR is still deenergized on account of the switcher being on section 2AT, relay 2XSR is still energized by its second stick circuit, and therefore contact 18 of relay 2XSR is open in the circuits for relay 2HR. Relay 2HR therefore still remains deenergized.

When the first switcher leaves section 2AT, contact 25 of relay 2ATR becomes opened in the circuits for relay 2HR. Relay 2ATR, upon becoming energized, completes, at its contact 10, the circuit for energizing relay 2-2ATPR which, upon becoming energized, opens the stick circuit traced for relay 2XSR, causing relay 2XSR to be deenergized.

With contact 18 of relay 2XSR now again closed, and with contact 21 of relay 1ATR closed on account of the second switcher occupying section 1AT, relay 1HR will again become energized by its pickup and stick circuits previously described. Yellow lamp Y of signal 1S will now again become lighted, and therefore the second switcher can enter the switching area at point a. The operation of the apparatus in response to the second switcher entering the switching area will then be as previously described for the first switcher.

I shall now assume that the second switcher leaves the switching area at point a instead of at point b. When the second switcher enters section 1T while leaving the switching area at point a, deenergizing relay 1TR, relay 1XSR will become energized by its pickup and stick circuits similarly to the manner in which relay 2XSR became energized in response to the first switcher leaving the switching area at point b.

When the second switcher now enters section 1AT, contact 21 of relay 1ATR will become closed in the circuits for relay 1HR, which will, however, be open at contact 19 of relay ENSR and at contact 20 of relay 1XSR.

When the second switcher leaves section 1T, relay ENSR will become energized by a second pickup circuit which is the same as the first pickup circuit traced for this relay except that it includes contact 17 of relay 1XSR instead of contact 16 of relay 2XSR.

Also, when the second switcher leaves section 1T, relay 1-1ATPR will still be deenergized on account of relay 1ATR being deenergized, and therefore relay 1XSR will

still be retained in the energized condition by its second stick circuit. With relay 1XSR thus energized, its contact 20 will be open, so that neither relay 1HR nor relay 2HR can become energized.

When the second switcher leaves section 1AT, contact 21 of relay 1ATR will become opened in the circuits for relay 1HR. Relay 1-1ATPR will now become energized because of the closing of contact 6 of relay 1ATR. Relay 1XSR will therefore become deenergized, and all parts of the apparatus will then again be in the normal condition in which they are shown in the drawing.

I have described the operation of the apparatus shown in the accompanying drawing when switchers enter the given switching area a—b in the eastbound direction and then leave in either the eastbound or the westbound direction. It is believed that, in view of such description, the operation of the apparatus when a switcher enters in the westbound direction at point b can be readily traced from the accompanying drawing.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus for controlling movements of railway vehicles onto a given stretch of track which is not equipped with traffic responsive means, comprising in combination, traffic governing means located adjacent each entrance point for said given stretch of track for governing traffic movements onto the given stretch of track at the corresponding entrance point, first traffic responsive means located in the rear of the traffic governing means for each of said entrance points, second traffic responsive means located in advance of the traffic governing means for each of said entrance points, means controlled by the said first traffic responsive means in response to a first vehicle approaching in the rear of the traffic governing means for any corresponding entrance point for placing the corresponding traffic governing means in condition to direct the said first vehicle to enter the said given stretch of track, means controlled by the said second traffic responsive means in response to said first vehicle passing the corresponding traffic governing means for placing all of said traffic governing means in condition to stop a second vehicle, and directional means controlled by both the traffic responsive means for any entrance point in response to said first vehicle leaving said given stretch of track at the corresponding entrance point for preparing the traffic governing means for all of the entrance points for directing a second vehicle to enter said given stretch of track at any entrance point in response to control of the first traffic responsive means at the corresponding entrance point by said second vehicle.

2. Railway traffic controlling apparatus for controlling movements of railway vehicles onto a given stretch of track which is not equipped with traffic responsive means, comprising in combination, traffic governing means located adjacent each entrance point for said given stretch of track for governing traffic movements onto the given stretch of track at the corresponding entrance point, first traffic responsive means located in the rear of the traffic governing means for each of said entrance points, second traffic responsive means located in advance of the traffic governing means for each of said entrance points, means controlled by the said first traffic responsive means in response to a first vehicle approaching in the rear of the traffic governing means for any corresponding entrance point for placing the corresponding traffic governing means in condition to direct the said first vehicle to enter the said given stretch of track, means controlled by the said second traffic responsive means in response to said first vehicle passing the corresponding traffic governing means for placing all of said traffic governing means in

condition to stop a second vehicle, traffic responsive means located adjacent each exit point for said given stretch of track, and means controlled by the traffic responsive means for any of said exit points in response to said first vehicle leaving said given stretch of track at the corresponding exit point for preparing the traffic governing means for each entrance point for directing a second vehicle to enter said given stretch of track at any entrance point in response to control of the first traffic responsive means at the corresponding entrance point by said second vehicle.

3. Railway traffic controlling apparatus for controlling movements of railway vehicles onto a given stretch of track which is not equipped with traffic responsive means, comprising in combination, traffic governing means located adjacent each entrance point for said given stretch of track for governing traffic movements onto the given stretch of track at the corresponding entrance point, first traffic responsive means located in the rear of the traffic governing means for each of said entrance points, second traffic responsive means located in advance of the traffic governing means for each of said entrance points, a circuit closed by the said first traffic responsive means for any entrance point in response to a first vehicle approaching in the rear of the traffic governing means for the corresponding entrance point for placing the corresponding traffic governing means in condition to direct the said first vehicle to enter the said given stretch of track, means controlled by the said second traffic responsive means in response to said first vehicle passing the corresponding traffic governing means for opening said circuit for placing all of said traffic governing means in condition to stop a second vehicle, and directional means controlled by both the traffic responsive means for any entrance point in response to said first vehicle leaving said given stretch of track at the corresponding entrance point for preparing the traffic governing means for each entrance point for directing a second vehicle to enter said given stretch of track at any entrance point in response to control of the first traffic responsive means at the corresponding entrance point by said second vehicle.

4. Railway traffic controlling apparatus for controlling movements of railway vehicles onto a given stretch of track which is not equipped with traffic responsive means, comprising in combination, traffic governing means located adjacent each entrance point for said given stretch of track for governing traffic movements onto the given stretch of track at the corresponding entrance point, first traffic responsive means located in the rear of the traffic governing means for each of said entrance points, second traffic responsive means located in advance of the traffic governing means for each of said entrance points, a circuit closed by the said first traffic responsive means for any entrance point in response to a first vehicle approaching in the rear of the traffic governing means for the corresponding entrance point for placing the corresponding traffic governing means in condition to direct the said first vehicle to enter the said given stretch of track, a master control relay which is normally energized but which becomes deenergized by the second traffic responsive means for any entrance point in response to said first vehicle entering said given stretch of track at the corresponding entrance point, means controlled by said master control relay upon becoming deenergized for opening said circuit and thereby placing all of the traffic governing means in condition to stop a second vehicle, and directional means controlled by both the traffic responsive means for any entrance point in response to said first vehicle leaving said given stretch of track at the corresponding entrance point for again energizing said master control relay for preparing said circuit to again become closed in response to a first traffic responsive means for any of said entrance points controlled by a second vehicle for placing the corresponding traffic governing means in condition to direct said second vehicle to enter said given stretch of track.

5. Railway traffic controlling apparatus for controlling movements of railway vehicles onto a given stretch of track which is not equipped with traffic responsive means, comprising in combination, traffic governing means located adjacent each entrance point for said given stretch of track for governing traffic movements onto the given stretch of track at the corresponding entrance point, first traffic responsive means located in the rear of the traffic governing means for each of said entrance points, second traffic responsive means located in advance of the traffic governing means for each of said entrance points, a circuit closed by the said first traffic responsive means for any entrance point in response to a first vehicle approaching in the rear of the traffic governing means for the corresponding entrance point for placing the corresponding traffic governing means in condition to direct the said first vehicle to enter the said given stretch of track, a master control relay which is normally energized but which becomes deenergized by the second traffic responsive means for any entrance point in response to said first vehicle entering said given stretch of track at the corresponding entrance point, means controlled by said master control relay upon becoming deenergized for opening said circuit and thereby placing the corresponding traffic governing means in condition to stop a second vehicle, first traffic responsive means located adjacent each exit point for said given stretch of track, second traffic responsive means located between said given stretch of track and the first traffic responsive means for each of said exit points, a traffic control relay for each of said exit points, means controlled by the second traffic responsive means for each of said exit points for energizing the corresponding traffic control relay in response to a vehicle leaving the said given stretch of track at the corresponding exit point, means controlled by the first traffic responsive means for each exit point for then retaining the traffic control relay for the corresponding exit point energized as long as the second traffic responsive means is controlled by the vehicle leaving at the corresponding exit point, and means controlled by each of said traffic control relays upon becoming energized for effecting energization of said master control relay when a vehicle leaving said given stretch of track ceases to control the second traffic responsive means for the corresponding exit point.

6. Railway traffic controlling apparatus for controlling apparatus for controlling movements of railway vehicles onto a given stretch of track which is not equipped with traffic responsive means, comprising in combination, a first and a second track section adjacent each entrance and exit point for said given stretch of track, each said second track section being between the corresponding first track section and said given stretch of track, a track circuit for each of said track sections each including a source of current and a track relay, traffic governing means for each of said entrance points, a repeater relay for each of said exit points, a control circuit for each of said repeater relays each controlled by front contacts of the track relays for the section for the corresponding exit point, a traffic control relay for each of said exit points, a pickup circuit for each of said traffic control relays each controlled by a back contact of the second track section relay and a front contact of the repeater relay for the corresponding exit point, a first stick circuit for each of said traffic control relays each controlled by a back contact of the corresponding second track section relay, a second stick circuit for each of said traffic control relays each controlled by a back contact of the corresponding repeater relay, a master control relay, a stick circuit controlled by a front contact of each of said second track section relays for normally energizing said master control relay, a plurality of pickup circuits for said master control relay one for each of said exit points each controlled by a front contact of each of said track section relays and by a front contact of a corresponding traffic control relay, a control relay for the traffic governing means for each of said entrance points each energized

by a circuit controlled by a front contact of each of the second track section relays and by a front contact of the master control relay and by a back contact of each traffic control relay and of the first track section relay for the corresponding entrance point, and means controlled by the control relay for the traffic governing means for each entrance point for controlling the corresponding traffic governing means to authorize a vehicle to enter the given stretch of track if the control relay is energized and for controlling the corresponding traffic governing means to stop a vehicle from entering said given stretch of track if the control relay is deenergized.

7. Railway traffic controlling apparatus for controlling apparatus for controlling movements of railway vehicles onto a given stretch of track which is not equipped with traffic responsive means, comprising in combination, a first and a second track section adjacent each entrance and exit point for said given stretch of track, each said second track section being between the corresponding first track section and said given stretch of track, a track circuit for each of said track sections each including a source of current and a track relay, traffic governing means for each of said entrance points, a repeater relay for each of said exit points, a control circuit for each of said repeater relays each controlled by front contacts of the track relays for the sections for the corresponding exit point, a traffic control relay for each of said exit points, a pickup circuit for each of said traffic control relays each controlled to energize the corresponding traffic control relay in response to a vehicle entering the second track section for the corresponding exit point when leaving said given stretch of track, stick circuit means for each of said traffic control relays for then retaining the corresponding traffic control relay energized as long as either the second or the first track section for the corresponding exit point is occupied by the vehicle, a master control relay, a stick circuit controlled by front contacts of each of said second track section relays for normally energizing said master control relay, pickup circuit means for said master control relay controlled by a front contact of each of said second track section relays and controlled by said traffic control relays for energizing said master control relay when any one of said traffic control relays is energized, and means controlled by a front contact of each of said second track section relays and of said master control relay and by a back contact of each of said traffic control relays for controlling the traffic governing means for any of said entrance points to authorize a vehicle to enter said given stretch of track when the vehicle enters the corresponding first track section.

8. Railway traffic controlling apparatus for controlling movements of switchers onto a given switching area which is not equipped with traffic responsive means and which has one or more entrance points and has also one or more exit points which may also serve as entrance points for said switchers, the combination comprising, a first and a second track section for each of said points which serves as an entrance point or as an exit point or as both an entrance and an exit point, each said track section being adjacent a corresponding one of said points and between the corresponding first track section and the corresponding said point, a track circuit for each of said sections each including a source of current and a track relay, a signal for each of said entrance points for governing traffic movements onto said given switching area, a repeater relay for each of said exit points, an energizing circuit for each of said repeater relays each controlled by front contacts of both track relays for the corresponding exit point, a traffic control relay for each of said exit

points, a pickup circuit and a first stick circuit for each of said traffic control relays each controlled by a back contact of the second track section relay for the corresponding exit point and the pickup circuit also controlled by a front contact of the corresponding repeater relay, a second stick circuit for each of said traffic control relays each controlled by a back contact of the corresponding repeater relay, a master control relay, a stick circuit and one or more pickup circuits for said master control relay each controlled by a front contact of each of said second track section relays and each pickup circuit also controlled by a front contact of a corresponding traffic control relay, a signal relay for each of said signals, an energizing circuit for each of said signal relays each controlled by front contacts of all of said second track section relays and said master control relay and by back contacts of all said traffic control relays and of the first track section relay for the corresponding entrance point, and means controlled by each of said signal relays for controlling the corresponding signal to display a proceed or a stop indication according as the corresponding signal relay is energized or deenergized respectively.

9. Railway traffic controlling apparatus for controlling movements of switchers onto a given switching area which is not equipped with traffic responsive means and which has one or more entrance points and has also one or more exit points which may also serve as entrance points for said switchers, the combination comprising, a first and a second track section for each of said points which serves as an entrance point or as an exit point or as both an entrance and an exit point, each said second track section being adjacent a corresponding one of said points and between the corresponding first track section and the corresponding said point, a signal for each of said entrance points for governing traffic movements onto said given switching area, a repeater relay for each of said exit points, an energizing circuit for each of said repeater relays each normally energized but being deenergized in response to either track section for the corresponding exit point being occupied by a railway vehicle, a traffic control relay for each of said exit points, means controlled by a switcher upon entering a second track section while leaving said given switching area for energizing a corresponding traffic control relay and for then retaining the traffic control relay energized until both track sections for the corresponding exit point are again unoccupied, a master control relay which is normally energized but becomes deenergized in response to any of said second track sections becoming occupied by a switcher, means controlled by any one of said traffic control relays if energized while all of the second track sections are unoccupied for again energizing said master control relay, a signal relay for each of said signals, means for energizing each of said signal control relays in response to a switcher entering the first track section for the corresponding entrance point while all the second track sections are unoccupied and the master control relay is energized and all the traffic control relays are deenergized, and means controlled by each of said signal relays for controlling the corresponding signal to display a proceed or a stop indication according as the corresponding signal relay is energized or deenergized respectively.
